United States Patent Office.

JOHN R. ROSE AND EDWARD L. CALEY, OF PHILADELPHIA, PENNSYLVANIA, ASSIGNORS TO COX, WHITEMAN & COX, OF SAME PLACE.

Design No. 4,902, dated May 9, 1871.

DESIGN FOR PLATES OF A COOKING-STOVE.

The Schedule referred to in these Letters Patent and making part of the same.

We, JOHN R. ROSE and EDWARD L. CALEY, of the city of Philadelphia, in the State of Pennsylvania, have invented and produced a new and original ornamental Design for the Plates of a Cooking-Stove, of which the following is a specification.

The nature of our design is fully represented in the accompanying photographic illustrations and diagrams, to which reference is made.

The ornaments for the top plate A, the ash-pit plate B, and the bottom plate C, consist of the respective edge-moldings $a' b' c'$, as shown in perspective by the photographic representations, and in transverse section by the diagrams 1 2 3.

The ornaments for each of the several door-plates of the stove consist of a bass-relief central figure, substantially in the form of an elongated Maltese cross, D, on a raised convex surface, d^1 , the base of which latter has four curved sides rising from a flat rectangular plane, d^2 , whose side and end boundaries are parallel with the edge-moldings d^3 of the door-plate.

On the flat surface which is between the edge-molding d^3 and the rectangular plane d^2 there is an ornamental border, d^4 , consisting of numerous bass-relief

points or elevations arranged in lines crossing each other like lattice-work.

For identification we name this stove "superb cook."

Claim.

We claim as our invention—

The ornamental design for the plates of a cooking-stove, as shown, the same consisting of the following elements, viz.: First, the bass-relief cross D, the convex surface d^1 , and the rectangular flat plane d^2 , substantially as shown. Second, the border d^4 , consisting of bass-relief points arranged in rows crossing each other like lattice-work, substantially as shown. Third, the design and configuration of a cook-stove with plates A B C, having respectively the edge-moldings $a' b' c'$, as shown.
